United States Patent Office.

ISAAC FISHER, OF ST. LOUIS, MISSOURI.

Letters Patent No. 77,472, dated May 5, 1868.

IMPROVEMENT IN VISES.

The Schedule referred to in these Letters Patent and making part of the same.

TO ALL WHOM IT MAY CONCERN:

Be it known that I, ISAAC FISHER, of the city and county of St. Louis, in the State of Missouri, have invented a new and useful Improvement in Vises; and I do hereby declare the following to be a full, clear, and exact description thereof, sufficient to enable others skilled in the art to which the invention appertains to fully understand and use the same, reference being had to the accompanying drawings, which are made part of this specification, and in which—

Figure 1 is a front view of a vise and bench illustrating my invention.

Figure 2 is a vertical section of the same, the plane of section passing longitudinally through the horizontal axis, upon which the visé is supported and adjusted.

Figure 3 is a rear view, showing one of the bearings and the horizontal axis of the vise.

Similar letters of reference indicate corresponding parts in the several figures.

Vises have hitherto been mounted upon a vertical axis to enable the work griped between the jaws to be placed in the most convenient position to be operated upon by the file or whatever shaving, cutting, boring, or other tool may be applied. This adjustment has been found practically insufficient in many cases, and I have therefore devised a method of mounting the vise so as to render it adjustable upon a horizontal as well as a vertical axis, and I will now proceed to explain the invention in detail.

In the drawings, A may represent a vise, which may be constructed in the usual manner, that is to say, with two jaws actuated by a screw, or after any of the improved plans that may exist. I provide the vise with the customary vertical axis, B, upon which said vise may be swung around in a horizontal plane, and the threaded end of the axis B has a jaw-nut, C, whereby the vise may be rigidly retained in any position to which it may be thus moved.

While the vise is adapted by the axis B to be turned in a horizontal plane, as above described, it is supported by the seat D, of which the arm D' is a part or continuation. The arm D' is joined at its centre to the horizontal axis E, one of whose bearings is supplied by the semicircular plate F, which is rigidly attached to the bench G. The after-bearing is seen at F'. The free extremity of the arm D' carries a clamp, H, movable by means of the handle h, so as to be made to clamp or release the rim of the plate F, with which latter the axis of the arm D' is concentric.

The horizontal axis E enables the vise A to be adjusted in a vertical plane, as clearly shown by red lines in fig. 1, and the vise, when moved under this adjustment, may be retained rigidly in the desired position by the clamp H.

The two axes B and E enable the position of the vise to be varied to such an extent and with such facility that the operator may work with the greatest convenience, without releasing the work from the jaws, and he may also move the vise as may be required to bring the work within the range of the light.

The seat D, arm D', and axis E are designed to constitute but a single casting.

Having thus described my invention, what I claim as new, and desire to secure by Letters Patent, is—

The improved vise A, the same having two axes or centres of adjustment, arranged substantially as described.

The above, signed on this 6th day of April, 1868.

ISAAC FISHER.
